UNITED STATES PATENT OFFICE.

FRANZ X. WAGNER, OF NEW YORK, N. Y., ASSIGNOR TO UNDERWOOD TYPEWRITER COMPANY, OF NEW YORK, N. Y., A CORPORATION OF NEW JERSEY.

RIBBON MECHANISM FOR TYPE-WRITERS.

No. 876,309.

Specification of Letters Patent.

Patented Jan. 7, 1908.

Original application filed November 12, 1904, Serial No. 232,413. Divided and this application filed May 18, 1905. Serial No. 260,984.

To all whom it may concern:

Be it known that I, FRANZ X. WAGNER, a citizen of the United States, resident of the borough of the Bronx, city, county, and State of New York, have invented certain new and useful Improvements in Ribbon Mechanism for Type-Writers, of which the following is a specification.

My invention relates to typewriters and has for its object to improve the ribbon mechanism of such machines. The invention will be fully described hereinafter and the features of novelty will be pointed out in the appended claims.

15 The present application is a division of one filed by me in the United States Patent Office, on November 12, 1904, Serial No. 232,413.

Reference is to be had to the accompanying drawings in which.

Figure 1 is a sectional elevation of a type-writing machine embodying my improvements; Fig. 2 is an elevation of such machine from the left side with parts in section; 25 Fig. 3 is a sectional plan of the ribbon reverse mechanism on the line 3—3 of Fig. 1; Fig. 4 is a rear elevation taken as indicated by the arrows 4 in Fig. 3; Fig. 5 is a section on line 5—5 of Fig. 4; Fig. 6 is a section on line 6—6 of Fig. 4; Fig. 7 is a section on line 7—7 of Fig. 3 and Fig. 8 is a detail rear view of certain parts of the ribbon mechanism.

In the drawings, the keys 1 are mounted on levers 2, which are fulcrumed at 3, preferably in such a manner as to be easily removable. Each key lever by means of a pin and slot connection 4 operates an elbow lever 5, fulcrumed at 6. The elbow levers are preferably removable from their fulcrum, being normally held by a locking bar 7. Each elbow lever is connected by a link 8, with a type bar 9 normally resting on the cushion 10. The type bar is provided with an opening and seat for the reception of the pivot 11, carried by the segment 12, and preferably the type bar is held in place by means of a latch 13, which the spring 14 tends to throw into a position in which it closes the opening for the insertion of the pivot 11. The handle of the latch is indicated at 13^a. Each key lever is provided with a toe 2^a adapted to engage a universal bar 15 which extends transversely of the machine, and has at each end a lug pivotally connected at 15^a with a suspended link 16

fulcrumed on the machine at 16^a. A bar 17 extends rearwardly from the center of the universal bar 15 and is secured at its rear end to a cross bar 18 fulcrumed on the frame at 18^a. The bar 17 carries an escapement pawl 19, which normally arrests a tooth of the escapement wheel 20 mounted on the shaft 21. The bar 17 is further provided with a projection 22 in engagement with the stop pawl 23, fulcrumed on the frame of the machine at 24, and pulled against the projection 22 by an adjustable spring 25. As the universal bar 15 is moved rearward the pawl 19 is disengaged from the escapement wheel 20 and the stop pawl 23 is swung into the path of said wheel 20, this operation permitting the escapement wheel 20 to rotate in the direction of the arrow in Fig. 3. The operation is reversed as the universal bar again moves forward, to the position shown in Fig. 1, partly under the influence of the spring 25 but chiefly under the influence of the carriage propelling spring.

At its upper end the shaft 21 is provided with a loose pinion 26, engaging a rack 27 on the carriage 28. This pinion is connected to turn with the shaft in the feed direction, by means of a disk 21^a rigid on the shaft 21 and spring pressed pawl 21^b carried by said disk. This allows the carriage to be moved by hand in a direction contrary to the feed movement without turning the shaft 21.

A pinion 29 is loosely mounted on the shaft 21, and is normally driven in the same direction as the shaft during the feed movement, by a spring-pressed pawl 29^a secured to a disk 29^b rigid with the shaft 21. These parts correspond to those designated by 21^a and 21^b, except that the pawls 21^b and 29^a face in opposite directions and thus act oppositely. The pinion 29 meshes with a toothed wheel 30, rigidly connected with a bevel wheel 31 engaging another bevel wheel 32 upon a sleeve 33 surrounding a shaft 34 extending transversely of the machine. An arm 35 (Figs. 3 and 4) projected from the frame of the machine holds the bevel wheel 32 against longitudinal movement, and in permanent engagement with the bevel wheel 31. The shaft 34 is capable of sliding lengthwise in the sleeve 33 and in bearings 36, but is held to rotate with the wheel 32, as by a feather and groove connection. Near its ends the shaft 34 carries rigidly two bevel pinions 37, adapted to engage bevel wheels 105

110

38 on shafts 39. It will be understood from Figs. 3 and 4 that only one of the sets of wheels 37, 38 is in mesh at a time. Each shaft 39 is in driving connection by means of 5 bevel gearing 40, 41, with the shaft 42 of one of the ribbon spools 43, contained in the holders 44. These spools and holders may be of the usual construction, the ribbon 45 on its way from one spool to the other passing 10 through a ribbon guide 46 disposed adjacent to the printing point. This ribbon guide receives a rearward and upward movement, at each operation of a key lever, by means of a lever 47 (Fig. 1), having a pin and slot connection with the bar 17 and fulcrumed at 48. The upper end of this lever has a pin and slot connection with an elbow lever 49 fulcrumed at 50 and carrying the ribbon guide 46; the 15 swinging of this lever is limited by a screw 20 51, extending through a slot 49^a. Thus, each time the escapement is operated to advance the carriage in its step by step feed movement, the ribbon feed just described will also be actuated, through the medium 25 of the mechanism just described. This fulcrum 48 may be raised or lowered to vary the throw of the lever 49 and held in such adjusted position by means of the set screw 48^a. In order to adjust the guide 46 so that 30 it will always reach the normal or printing position, notwithstanding the difference in the throw of the lever 49, due to the adjustment of the pivot 48, the said guide 46 is provided with a slot which coöperates with the 35 screw 46^a. The said guide 46 is thus adjustable up or down on the elbow lever 49. By having the fulcrum 48 adjustable, different widths of ribbon may be used; that is, if a wide ribbon is used, it is desirable in order to 40 use all parts of said ribbon to raise the lower part thereof a greater distance than if a narrower ribbon is used. By adjusting the pivot 48, this extra throw can be secured. This adjustment is also valuable where a 45 large number of copies are written at the same time, for by lowering the pivot 48, the distance between the platen surface and the initial position of the guide 46 can be increased to make way for the large number of 50 sheets and thus prevent smudging.

In order that the direction of the ribbon feed may be reversed when the ribbon 45 is almost entirely unwound from one of the spools 43, the following mechanism is provided (Figs. 1, 2, 3 and 4): The shaft 34 is provided adjacent to the bevel pinions 37 with collars 34^a which are adapted to be engaged by forked push fingers 52 mounted on shafts 53 and under the influence of 55 springs 54 which tend to throw said fingers toward each other. The fingers 52 are normally held stationary, ready to be thrown inward by the respective springs 54, by means of latches 55 projected into the paths of arms 60 65 56 secured to shafts 53. These latches are

secured to vertical shafts 57 and are pressed toward the paths of the arms 56 by springs 58. The movement of the latches may be limited by making them with forked portions, embracing members 59 of the machine frame. 70 Each shaft 57 carries at its upper end an arm 60 having a guide 61 for the ribbon 45. Near each end of the ribbon is secured the usual metal loop or projection of such a size that it cannot pass through the guides 61. When 75 this loop engages the said guide, the guide will be swung aside so as to bring the corresponding latch 55 away from the arm 56. This will release the shaft 53 and cause the spring 54 and push finger 52 to shift the shaft 80 34 so that its opposite end will come into driving connection with the respective bevel wheel 38, thus reversing the direction of the ribbon movement. The push fingers 52 are brought back to their original (set) position 85 in any suitable manner, for instance, by the carriage shift mechanism, as fully described hereinafter. Fig. 3 shows the position of the parts immediately after the shaft 34 has been shifted to the right and before the arm 56 on 90 the left-hand side has been reset by the operation of the carriage shift.

In order to prevent any accidental movement of the reversing shaft 34 I may locate a spring pressed ball 62 in one of the bearings 95 36 (Figs. 4 and 5) to engage one or the other of two grooves 34^b in the shaft 34 according to the position of said shaft.

As stated hereinbefore the carriage shift mechanism may be employed for the purpose 100 of setting the ribbon reverse mechanism. For this purpose the lifting bars 63 are provided with hooks 64, pivoted at 64^a, adapted to engage the ends of the arms 56. Each hook 64 is connected with a spring 64^b, the 105 upper end of which slides in the guide 64^a on the frame of the machine. Thus, when the lifting bar 63 is in its lower position, the spring holds the hook in the projecting position shown in Fig. 2, but as the lifting bar 110 rises, the hook will be swung on its pivot in the direction of the arrow to finally clear the arm 56 after the latch 55 has been set. Thus when the carriage is shifted to its upper position by depressing either of the shift keys 115 65, one of which is located at each side of the machine, the hooks 64 will engage and raise the arms 56 unless these arms should happen to be already in their upper or set position. The latches 55 or the portion of the arms 56 120 engaging them are of course beveled as shown in Fig. 7, or otherwise so constructed that the latch will be swung aside when the arm 56 is raised from its lower to its upper position.

In order that either one of the ribbon spools 43 may be rotated by hand, I provide a handle 34^b on the shaft 34, as shown in Fig. 4, said handle being clear of the machine frame in either position of the shaft 34. 130

Various modifications may be made without departing from the nature of my invention.

What I claim as new and desire to secure by Letters Patent is:

1. In a typewriter or like machine, a ribbon reverse mechanism comprising a longitudinally shifting shaft having gears for driving one ribbon spool or the other, collars rigidly carried by said shaft between the gears, and rigid shifting fingers arranged between each of the collars and each of the gears and adapted to directly engage the collars.
2. In a typewriter or like machine, a ribbon reverse mechanism comprising a longitudinally shifting drive shaft having gears for driving one ribbon spool or the other, spring-pressed push fingers for shifting said shaft, mechanism for putting the springs of said fingers under tension, latches for holding the fingers in their set position, and means operated by the movement of the ribbon, for releasing said latches.
3. In a typewriter or like machine, a ribbon reverse mechanism comprising a longitudinally shifting shaft having gears for driving one ribbon spool or the other, collars rigidly carried by said shaft, and rigid shifting fingers each adapted to directly engage one of said collars.
4. In a typewriter, or like machine, a ribbon reverse mechanism comprising a longitudinally shifting shaft having means for driving one ribbon spool or the other, spring-pressed push fingers, pivoted adjacent to the ends of said shaft, arms mounted to turn together with said push fingers, latches normally in the paths of said arms, connections from said latches to the ribbon to swing them aside when the ribbon is nearly unwound from the corresponding ribbon spool, and means arranged to engage said arms for setting the push fingers ready for operation.
5. In a typewriter, or like machine, a ribbon reversing mechanism comprising a longitudinally shifting drive shaft adapted to drive one ribbon spool or the other, spring-pressed push fingers for shifting said shaft, an arm connected with each of said fingers, mechanism connected with the carriage shift key for engaging said arms and bringing the push fingers to their set position, and latches arranged to hold said arms and adapted to be swung away from them by the ribbon when the ribbon nears its end.
6. In a typewriter, or like machine, a universal bar operated by the keys, a lever extending upwardly and arranged to be swung by the movement of said universal bar, an elbow lever operated by said swinging lever, a ribbon guide secured rigidly to said elbow lever, and means for permitting the adjustment of said ribbon guide on said elbow lever.

by the movement of said universal bar, an elbow lever operated by said swinging lever and a ribbon guide secured rigidly to said elbow lever.

7. In a typewriter, or like machine, a ribbon reversing mechanism comprising a longitudinally shifting drive shaft adapted to drive one ribbon spool or the other, spring-pressed push fingers for shifting said shaft, an arm connected with each of said fingers, lifting bars connected with the carriage shift key, devices mounted on said lifting bars for engaging said arms to bring the push fingers to their set position, and latches arranged to hold said arms and adapted to be swung away from them by the ribbon when the ribbon nears the end.

8. In a typewriter, or like machine, a ribbon reversing mechanism comprising a longitudinally shifting drive shaft adapted to drive one ribbon spool or the other, spring-pressed push fingers for shifting said shaft, an arm connected with each of said fingers, lifting bars connected with the carriage shift key, devices mounted on said lifting bars for engaging said arms to bring the push fingers to their set position, means for moving said devices out of the path of said arms after said fingers have been set, and latches arranged to hold said arms and adapted to be swung away from them by the ribbon when the ribbon nears its end.

9. In a typewriter or like machine, a swinging ribbon guide arranged adjacent to the printing point, a universal bar arranged to be operated by the keys, a connecting lever for transmitting the motion of the universal bar to the ribbon guide, the pivot of said connecting lever being adjustable in the direction of the lever's length for the purpose of varying the throw of the ribbon guide.

10. In a typewriter or like machine, a universal bar operated by the keys, a lever extending upwardly and arranged to be swung by the movement of said universal bar, an elbow lever operated by said swinging lever, a ribbon guide secured rigidly to said elbow lever, and means for permitting the adjustment of said ribbon guide on said elbow lever.

In testimony whereof, I have hereunto set my hand in the presence of two subscribing witnesses.

FRANZ X. WAGNER.
